UNITED STATES PATENT OFFICE.

JULIUS B. KOEHLER, OF CINCINNATI, OHIO, ASSIGNOR TO THE MONITOR STOVE COMPANY, OF CINCINNATI, OHIO, A CORPORATION OF OHIO.

HOT-AIR FURNACE.

1,411,037.

Specification of Letters Patent. Patented Mar. 28, 1922.

Application filed November 15, 1921. Serial No. 515,412.

To all whom it may concern:

Be it known that I, JULIUS B. KOEHLER, a citizen of the United States, and residing at Cincinnati, in the county of Hamilton 5 and State of Ohio, have invented a new and useful Improvement in Hot-Air Furnaces, of which the following specification is a full disclosure.

This invention relates to an improvement 10 in hot-air furnaces of a type designated as "pipeless," wherein three concentric cylindrical casings are relatively spaced and disposed about a heater to form an inner main hot-air chamber and up-passage, and a cold- 15 air duct or down passage, the two inner casings spaced to form the outer cold-air and the inner warm-air passages, by an upwardly circulating air passage as an insulator partition between said warm and cold- 20 air passages, to prevent reciprocal radiation between said main hot-air chamber and passage, and cold-air passage or duct.

This invention, as an improvement in furnaces, is generally related to Patent No. 25 1,346,801, granted to William J. Doyle and Justus J. Wollenhaupt, July 13, 1920. As shown in this patent and as illustrated in Fig. 1, the hot-air chamber and passage is connected at its top centrally of a floor register, and the cold-air passage or duct is connected to the same register marginally thereof. The hot-air chamber and passage and the cold-air duct or passage communicate at a point below the heating zone, and 30 the inner casing or drum of the double walled insulating partition, stops short of the register, allowing communication at that point between the restricted partition passage and the hot-air chamber or passage.

40 The double-walled insulating partition is intercepted circumferentially at the front of the furnace by the ash-pit and combustion chamber hoppers or snouts, the respective ends of the spaced casings, forming the insulating partition, being outwardly turned and fastened to the outer casing, thus forming a forward extension of the hot-air chamber and passage about said hoppers, and also forming extensions of the insulating 45 partition thereabout, and a horizontal division wall between the cold-air passage and warm-air chamber. In order to close the segmental opening above the hot-air chamber over the hoppers and between the insulating partition and the outer casing, to

prevent passage of hot-air into the cold-air duct, a segmental iron division plate has heretofore been used, for bridging and sealing the opening, as shown in the above mentioned patent.

In practice it has been found that radiation takes place from the hot-air chamber and passage, through the plate, upwardly to the cold-air duct, whereby the circulation of the cold air at this point is impaired, which condition materially interferes with the general heater circulation, as it is essential that the cold-air passage always be maintained as such, and not connected into a hot-air passage by heat radiating through the dividing walls.

The main object of this invention is therefore to improve the general heating efficiency of the type of furnace called "pipeless," and described in the aforementioned patent, by preventing the production of counter currents, within the cold-air duct, caused by radiation through the division plate, the object being accomplished by providing a hollow box-like thin-walled division plate permitting communication between the cold-air duct or passage and the interior of the double-walled insulating partition, in such a manner that any radiant heat delivered through the bottom of the division plate and at the interior of the same, will be mixed with downwardly traveling cold-air, and syphoned upwardly through the double-walled partition, by the heated air therewithin and delivered to the register.

Other objects and certain advantages will be disclosed in the description of the drawings, forming a part of this specification, and special reference is made to said drawings, in which:

Fig. 1 is a central vertical perspective section illustrating the application of my invention in a pipeless furnace.

Fig. 2 is a fragmentary plan section showing the disposition of my improved division plate above the clean-out snout.

Fig. 3 is a vertical section on line 3, 3, Fig. 2, looking in the direction of the arrows.

Fig. 4 is a view, similar to Fig. 3, on line 4, 4, Fig. 2, parts thereof being broken away to better illustrate the construction.

Fig. 5 is an enlarged detail section vertically through the clean-out spout, showing my division plate placed thereabove.

Fig. 6 is a section on line 6, 6, Fig. 5, broken away to show one manner of connecting the heater drums or casings to the ends of the division plate.

5 Fig. 7 is a bottom plan of the detached plate.

Referring particularly to Fig. 1 of the drawings, 1 designates the ash-pit of the heater structure accessible through a hopper 10 or snout closed by a door at the front of the furnace. 2 is the fire-box, 3 the fire-box dome or combustion chamber connected by a hopper or snout and closed by a door at the front of the furnace, and 4 is the hot-air radiator connected at its rear with the smoke pipe, and having a clean-out snout at its forward side closed by a suitable door. The snouts of the various elements of the heater connect with a face plate which may 15 be regarded as a part of the outer furnace casing. A hot-air chamber is formed about the above-mentioned parts or heater by a double-walled insulating partition comprising an inner drum or casing 11 and a second 20 drum or casing 12 relatively slightly spaced from the drum 11 to form a hot-air circulating space or channel 13, between the drums or casings, for the purpose of preventing reciprocal radiation between the hot-air 25 chamber and the cold-air duct 14, formed between the insulating partition and the outer furnace casing 15. The cold-air duct and hot-air chamber communicate below the heating zone, and the bottom of the partition is spaced and supported above the floor 30 by suitable stanchions. The upper part of the partition is constricted directly above the radiator 4, by detachable conical and spaced drum sections 16, 16', forming an 35 expansion chamber 10, the upper truncated ends of which are in turn detachably connected to pipe sections 17, 17', the section 17' being connected to a floor register 20, while the inner section 17 stops short of the 40 register to allow communication between the passage 13 and the hot-air chamber and passage 10. The outer furnace casing 15 is connected with an upper drum section 21, circular at its bottom periphery and 45 rectangular at its top, forming between itself and the section 16' an enlarged substantially concentric passage 22. The drum section 21 is connected marginally of the register 20, through a rectangular pipe section 23. A 50 cold-air duct or passage and a hot-air chamber and passage are thus formed and insulated from one another by a double-walled partition, providing a narrow heat circulating space and acting as a screen to prevent 55 mutual radiation between said duct and said chamber and passage.

The casings 11 and 12 at a point each side of the hoppers and clean-out snout are respectively bent and forwardly directed as 60 at 29, 30, and attached to the casing 15 or to

the front face plate 15', forming parallel terminal continuations of the channel 13 at each side of the hoppers and clean-out snout and forming also a continuation of the hot-air chamber forwardly to the door 70 plate. As herebefore stated, a segmental opening is formed above the forward extension of the hot-air chamber on both sides of the hoppers and clean-out snout and between the insulating partitions and the 75 outer casing 15, which it is the object of the invention to bridge and close in such a manner as to prevent radiation or circulation between the hot-air chamber and passage and cold-air conductor passage at this 80 point. To this end, a perforated hollow segmental box-like horizontal division plate or wall is provided, the bottom of which may rest upon the clean-out snout. The division 85 plate or spaced double-walled cross-partition is interiorly connected at its ends with the passage 13 of the double-walled vertical partition (see Figs. 3 and 4), to provide for hot-air circulation between the passage and the interior of the division plate or wall. 90 upwardly and into the constricted or conical section of said partition, and thence to the register. The division plate further functions to siphon the down-coming cold air which enters the interior of the plate and to 95 mix the same with any radiated heat delivered through the bottom of the plate at its interior, carrying the same upwardly into the channel 13 and thus preventing the entrance of hot air into the cold-air duct above 100 the division plate, to the impairment of general heater efficiency. The top 31 of the hollow division plate is provided with two rows of perforations, an inner row 32 and an outer row 33 respectively in connection 105 above the division plate with the passages or chambers 13, 22, the passage 22 being a continuation of the passage 14.

Figs. 2, 4 and 5 best show the relations of the division wall to the cold and hot-air 110 ducts or passages. The bottom 34 extends short of the ends of the wall to form rectangular openings in direct communication with the forward extensions of the passage 13 beneath the division wall. The ends of this bottom plate 24, marginally of these openings, are extended downwardly and are suitably fastened as at 35 to the upper edges of the forwardly disposed extensions 29 of the drum 11, while the upper ends 30 of the drum 12 abut and are fastened to the ends of the plate, as at 36. As constructed, air passing upwardly in the laterally extending portions of the circulating space 13 will enter the horizontal air space at each end of 115 the plate and will pass upwardly through the openings 32 and continue upwardly to the channel 13 above the plate or box, and thence to the register and into the room.

The detailed connection of the drums with 120

my improved division plate or hollow cross wall may vary, but essentially the channel or passage of the insulating partition and of the cold-air duct or passage above the plate, 5 will inter-communicate interiorly thereof to prevent radiation of the hot-air to the said cold-air duct.

Descending air entering the interior of the horizontal hollow division wall will absorb 10 the heat radiating from the lower plate 34 and then pass upwardly through the opening 32 into the intermediate or insulating space 13.

Having described my invention, I claim:

- 15 1. In a hot-air single register furnace, the combination with a heater having forwardly extending feed and clean-out snouts, an outer casing around said heater connecting with said snouts, a double-walled inner casing 20 ing between said heater and said outer casing, spaced therefrom to provide an outer down cold-air passage between said outer casing and inner double-walled casing, an up hot-air passage between the heater and 25 the double-walled inner casing, said passages communicating near the base of said furnace and said double-walled inner casing, providing an insulating space between said up and down passages, said inner casing ex- 30 tending forwardly and connecting with said outer casing, providing opposite double-walled side walls about said snouts, and a box-like division plate connecting said side walls above said snout, the interior of the 35 box-like division plate communicating with the insulating space of the said inner casing, with the space of the double-walled side walls thereof and with the cold-air passage above said division plate.
- 40 2. In a hot-air single register furnace, the combination with a heater having forwardly extending feed and clean-out snouts, an outer casing around said heater connecting with said snouts, a double-walled inner casing 45 ing between said heater and said outer casing spaced therefrom to provide an outer down cold-air passage and an inner up hot-air passage, the said passages communicat- 50 ing near the bottom of said furnace and being connected to a common register at their tops, said double-walled inner casing pro- 55 viding an insulating space between said pas- sages, said inner double-walled casing ex- tending forwardly and connecting with said outer casing to form side walls about said snouts and providing extensions of said insulating space, and a hollow division plate 60 connecting said side walls above said snout, the interior of said hollow division plate communicating with the insulating space of said double-walled insulating casing with the space between the side extensions of said casing and with the cold-air passage above said division plate.
- 65 3. In a hot-air single register furnace, the combination with a heater having forwardly extending feed and clean-out snouts, an outer casing around said heater connecting with said snouts, a double-walled inner insu- 70 lating casing, spaced therefrom, to provide a down cold-air passage and an up hot-air passage, the said passages communicating near the bottom of said furnace and being connected to a common register at their tops, said double-walled inner casing providing 75 an insulating space between said passages, said inner double-walled casing extending forwardly and connecting with said outer casing, to form double-walled side walls about said snouts, and to provide forward 80 extensions of said insulating space, and a hollow division plate connecting said side walls and comprising a metallic box having openings in its bottom communicating with the spaces between said double-walled side 85 walls, and having rows of openings in its top communicating respectively with said hot and cold-air passages above said snouts.
- 90 4. In a hot-air furnace, a heater having forwardly projecting snouts, a plurality of concentric casings about said heater, spaced from one another and from said heater, combining to provide an outer cold-air down- 95 passage and an inner hot-air up-passage, said passages communicating at their base, the casings forming the intermediate pas- 100 sage, extending at an angle at opposite sides of the heater snouts, and connecting with the outer casing, and a hollow horizontal dividing wall, providing a connecting wall for said angle extension of said inner casing 105 above said snouts, to divide the intermediate hot-air passage from said outer cold-air passage, and provide an air circulating insulating space therebetween, connecting with said cold-air passage and intermediate air circulating passage.
- 110 5. In a hot-air furnace, a heater having forwardly projecting snouts, a plurality of concentric casings about said heater, spaced from one another and from said heater, combining to provide three vertical air pas- 115 sages connecting at their bases, the inner casings thereof angled to connect with the outer casing at opposite sides of said snouts, and a spaced double-wall cross-partition 120 above said snouts, joining said casings to divide the outer passage from the inner, and provide a circulating air space therebetween communicating with said outer and intermediate passages.

In witness whereof, I hereunto subscribe my name, as attested by the two subscribing witnesses.

JULIUS B. KOEHLER.
